ADJUSTABLE CLAMPING MEANS FOR SHOESHINE FIXTURES

Filed Jan. 20, 1947

UNITED STATES PATENT OFFICE

2,440,871

ADJUSTABLE CLAMPING MEANS FOR
SHOESHINE FIXTURES

James G. Nevin, Toronto, Ontario, Canada

Application January 20, 1947, Serial No. 723,030

7 Claims. (Cl. 15—267)

1

This invention relates to improvements in shoeshine fixtures of the kind in which a shoe is placed and held during the time it is being cleaned and polished.

The invention has for its major object to provide a supporting fixture with a novel clamping mechanism by which a shoe is firmly secured by movement of a cam lever. The cam lever operates to advance a heel support into binding engagement with the heel of a shoe and to press the toe portion of the shoe into wedging engagement with spaced ears on a sole plate whereby to firmly clamp the shoe in place. The heel support is connected by a clutch plate to a slide rod which is pulled by the cam lever in a clamping operation. The clutch plate enables the heel support to be adjusted to suit different sized shoes.

Another object of the invention is to provide in combination a lever for effecting the clamping of a shoe in a fixture and a detachable screw clamp for securing the fixture either to a vertical or horizontal support and devised to be locked in place by said lever when it is thrown to a locking position.

With these and other objects in view the invention consists in the novel combination and arrangement of the parts as described in the ensuing specification and shown in the accompanying drawing which forms a part thereof.

In the drawing,

Fig. 1 is a top plan view, partly in section, of a shoeshine fixture constructed in accordance with the present invention.

Fig. 2 is a side elevation of the fixture.

Fig. 3 is a bottom plan view of the fixture in which parts are broken away.

Fig. 4 is a fragmentary top plan view of the fixture depicting the cam lever in its locking position.

Fig. 5 is a perspective aspect of the detachable screw clamp in a vertical position.

Fig. 5A is a perspective aspect of the detachable screw clamp in a horizontal position.

Fig. 6 is a fragmentary bottom plan view of the fixture showing the cam lever in its locking position.

Fig. 7 is a front end view of the fixture.

Fig. 8 is a perspective view of the cam lever.

Fig. 9 is a longitudinal section of the heel plate.

The invention comprehends a support 10 forming a shoe rest, which may be made as a casting or a pressed metal body. The fore part 11 has a flat top face for seating the sole portion of a shoe and constitutes a sole plate. Upstanding ears 12 are provided on its toe end for wedging en-

2

gagement with the side edges of the receding toe part of the shoe.

On the rear heel part of the support 10 there is provided a loose plate 13 which seats the heel 5 of the shoe. This heel plate has rigid ears 13' disposed to engage the back of the heel and to co-act with the ears 12 in clamping the shoe against movement while it is being cleaned and shined. The heel plate is integrated with a clutch plate 16 which is inclined downwardly and forwardly therefrom and is apertured at 15 to slide on a rod 16. The hole 15 loosely receives said rod and enables the heel plate to be moved longitudinally of the support 10 to accommodate shoes of different sizes. In the present instance the longitudinally extending rod 16 is disposed in a cavity 17 having side walls 18 with which the clutch plate is engaged to preclude the heel plate from tilting to one side. Other means could be employed for this purpose if so desired.

The rod 16 is slidably supported by the vertical walls 19 and 20 of the support 10. The clutch plate has binding engagement with the rod by reason of its backward tilt when in its normal position, shown in Figs. 1 and 2, in which is supports the heel plate in operable position. It is merely necessary to tilt the unitary clutch plate and heel plate forwardly with respect to the heel part of the shoe rest in order to release the clutch plate so that it may slide along the rod for a shoe of a larger size. When a shoe is placed upon the fixture the heel plate is pushed forwardly by the user to bring its ears against the shoe heel. The heel plate in any position 25 to which it is set binds on the rod against movement rearwardly with respect to the heel part of the shoe rest. Means are employed to draw the rod forwardly toward the toe part of the shoe rest in order to effect the clamping of the shoe by and between the fore and aft ears 12 and 13'.

The said means comprises a cam lever 21 pivoted on the rod 16 to extend laterally of the support 10 at the front of the vertical wall 19 for swinging downwardly from a non-locking to 45 a locking position. About the fulcrum of the lever there are provided cam faces 22 extended rearwardly for engaging cam devices 23 which project from the front wall 19 so that movement of the lever to a locking position will cause it to be thrown forwardly axially of said rod to a position in which its cam faces rest on the crests of the cam devices 23. The lever is backed by a compression spring 24 shouldered by a pinned washer 25 on the outer end of the rod 16 whereby 50 the throw of the lever forces the rod forwardly

toward the toe part of the shoe rest. Accordingly the heel plate is brought into firm clamping engagement with the shoe heel. The spring accommodates any necessary yielding of the applied force. In the use of the fixture it is only necessary to throw the lever downwardly to the position, indicated in dash lines in Fig. 7, to clamp a shoe. To release the shoe the lever is thrown upwardly to the lateral position shown in full lines in Fig. 7. A spring 25 is employed to return the rod, and this spring need only be comparatively light in applied stress.

The fixture is preferably supplied with a screw clamp so devised that it can be used to attach it to either a vertical or horizontal support, as for instance the back or seat of a chair. The screw clamp is comprised of a U-shaped clamp, denoted as a whole by the reference character A, having a thumb screw 26 threadedly carried by one of its legs, 27, for tightening against a supporting member engaged with the opposite leg 28. The leg 28 is provided with a male element 29 of a dovetail joint and the back 30 is provided with a similar male element 31. The female element of the dovetail is supplied on the bottom of the support 10 to extend horizontally thereof and is denoted at 32. The said male and female elements are tapered through their lengths and the taper of the female element extends rearwardly of the support 10 so that either of the male elements may be slid therein with a rearward movement. As shown in Fig. 2, to use the screw clamp for connecting the fixture to a vertical support, such as the back B of a chair, the dovetail connection is made with the male element 31. When it is desired to attach the fixture to a horizontal support such as the seat of a chair the screw block is changed to a position at right angles to that shown in Fig. 2 by using the male element 29. An important feature is that the lever is utilized to prevent the screw clamp from becoming inadvertently detached while the fixture is being used. To this end the lever is provided with a detent lug 33 arranged to overlie and contact the frontal surface of the screw clamp when the lever is swung to a locking position as best shown in Fig. 6. When the lever is swung aside to a non-locking position the screw clamp is unobstructed and can be readily removed if need be.

Having described the selected embodiment of the invention it will be understood that such changes and variations may be resorted to as come within the ensuing claims.

What I claim is:

1. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate slidable with said heel plate adapted to have binding engagement with said rod when in an oblique position whereby to retain said heel plate against backward movement, and a manual device for drawing said rod forwardly to effect clamping of the shoe.

2. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate rigid

with said heel plate adapted to have clutching engagement with said rod when in an oblique position whereby to connect said heel plate thereto so that it is held against relative backward displacement.

3. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate extended downwardly and forwardly from said heel plate with a hole in it through which said rod passes to retain the heel plate against backward movement by a clutching engagement, and a manual device for drawing said rod forwardly to effect the clamping of the shoe.

4. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate on said heel plate having an aperture through which said rod extends to provide clutching engagement therewith when the clutch plate is in a backwardly tilted position, and a lever mechanism for drawing said rod forwardly to effect clamping of the shoe.

5. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate on said heel plate having an aperture through which said rod extends to provide for clutching engagement when the clutch plate is in a backwardly sloped position, and a cam lever adapted to draw said rod forwardly to effect clamping of the shoe.

6. A shoeshine fixture comprising a support providing a sole plate having spaced ears for wedging engagement with the toe portion of a shoe, a heel plate slidable lengthwise of said support having a part for abutment with the back of the shoe heel, a rod mounted to slide longitudinally on said support, a clutch plate rigidly carrying said heel plate and extended downwardly and forwardly therefrom, said clutch plate having an aperture through which said rod passes to retain the heel plate against relative

55 retrograde movement by a clutching engagement, a lever pivoted on said rod to swing about the axis thereof to a locking position and having a cam face about its fulcrum engaged with a cam surface on said support for imparting forward movement to the rod when the lever is thrown to its locking position, and abutment means connecting the lever to the rod for transmitting such forward movement to the rod to effect the clamping of the shoe.

7. In a shoeshine fixture, a support for a shoe, a screw clamp for attaching said support to a relatively non-movable support, an interfitting connection for attaching said screw clamp to said support, said interfitting connection consisting of a female member on said support and a male member on said screw clamp, said members being engageable by a sliding action; means for clamping a shoe on said support including a lever adapted to be thrown to a locking position, 70 and a detent device carried by said lever to engage

said screw clamp when the lever is in a locking position so as to prevent inadvertent disengagement of said interfitting connection.
